UNITED STATES PATENT OFFICE.

EDWARD P. KENDALL, OF BOWDOINHAM, MAINE.

HOPPER.

1,164,195.

Specification of Letters Patent. Patented Dec. 14, 1915.

Application filed December 24, 1914. Serial No. 878,898.

To all whom it may concern:

Be it known that I, EDWARD P. KENDALL, a citizen of the United States, residing at Bowdoinham, in the county of Sagadahoc 5 and State of Maine, have invented a new and useful Hopper, of which the following is a specification.

The present invention appertains to hoppers, and aims to provide a novel and improved 10 hopper for drawing off various materials from bins, and the like.

One of the objects of the invention is to provide a valve or shutter assembled with the hopper in a unique manner, for cutting 15 off the flow of material through the discharge opening of the hopper, the parts being so arranged that the material will run off of the valve or shutter and will not cling thereto or lodge thereupon when the 20 valve or shutter is opened.

Another object of the invention is to provide novel means for mounting the valve or shutter for movement, in a most effective manner, to open and close or control 25 the passage through the discharge opening of the hopper.

A still further object of the invention is the provision of a novel actuating mechanism for the cut-off valve or shutter.

It is also within the scope of the invention 30 to provide a hopper device of the nature indicated, which will be comparatively simple, compact, non-encumbering and inexpensive in construction, which may be readily assembled and taken apart, which is provided 35 with adjusting means for adjusting the valve or shutter relative to the actuating means, and which is convenient, efficient and thoroughly practical in use.

With the foregoing and other objects in view which will appear as the description 40 proceeds, the invention resides in the combination and arrangement of parts and in the details of construction hereinafter described and claimed, it being understood that 45 changes in the precise embodiment of the invention herein disclosed can be made within the scope of what is claimed without departing from the spirit of the invention.

The invention is illustrated in its preferred embodiment in the accompanying 50 drawing, wherein—

Figure 1 is a side elevation of the improved hopper, with the valve or shutter in closed position. Fig. 2 is a vertical section 55 of the structure, with the valve or shutter

swung open. Fig. 3 is a reduced bottom view of the structure, with the valve or shutter closed.

The hopper proper or hopper body 1 is 60 preferably in the form of a casting, and its upper edge is provided with an outstanding rim or flange 2 for bolting or otherwise securing the hopper to the bottom of a bin, or other support, so that the material may be 65 discharged or run into the hopper so as to be dispensed through the lower discharge opening 3 of the hopper. The discharge opening 3 is disposed obliquely or in an inclined position, and the side edges 4 of the 70 opening 3 are curved upwardly from the lower end of the inclined wall 5 of the hopper, to the lower end of the opposite wall 6 of the hopper. The walls 5 and 6 of the hopper are relatively long and short, so 75 that the curved edges 4 of the other walls of the hopper will be arranged as specified, and to dispose the discharge opening 3 in the oblique or inclined position. The cut-off valve or shutter 7, which is also prefer- 80 ably in the form of a casting, is curved to fit snugly against and move along the curved edges 4 and the side edges of the valve or shutter 7 are provided with upturned flanges or lips 8 extending partially over the re- 85 spective side walls of the hopper.

In order to mount the valve or shutter 7 for oscillatory movement to open and close the discharge opening 3 of the hopper, the side edges and flanges 8 of the valve are 90 provided with outstanding lugs or ears 9 between the upper and lower edges of the valve, and the end portions of a U-shaped or bail-like hanger rod 10 are engaged downwardly through the lugs or ears 9, while the 95 intermediate or yoke portion of the hanger rod 10 is fulcrumed or pivoted upon lugs 11 outstanding from the wall 5 of the hopper adjacent or immediately below the rim or flange 2 of the hopper. Thus, the intermediate or yoke portion of the rod 10 is pivotally engaged between the lugs 11 and hopper rim 2, against the wall 5 of the hopper, and the rod 10 straddles the hopper. The edges 4 and valve 7 are curved about 100 the axis of the yoke or intermediate portion of the rod 10, or a line running between the lugs 11 and hopper rim 2, so that when the valve is swung with the rod 10, it will move properly along the edges 4 of the discharge opening 3. Nuts 12 are threaded 105 upon the ends of the rod 10 and bear against 110

the ears or lugs 9 for holding the valve 7 snugly against the edges 4, it being noted that when the nuts 12 are loosened and removed, the valve 7 and rod 10 may be separated, and the rod and valve may then be removed from the hopper readily.

The actuating mechanism for opening and closing the valve 7, embodies a transverse rod or shaft 13 journaled through 10 bearings 14 secured to the rim 2 of the hopper at the upper end of the wall 6, the rod or shaft 13 having a downwardly projecting or depending lever arm 15 at one side of the hopper, and a similarly projecting or depending arm 17 adjacent the wall 6 of the hopper. The lower end of the lever arm 15 is equipped with a suitable handle 16 in order that the lever 15—17 may be readily swung for controlling the valve. The arm 20 17 is connected to the valve 7 by means of a link 18, which is provided with a fork or bifurcated portion 19 at one end straddling the lower or free end of the arm 17, and pivoted thereto by means of a bolt or pivot 25 element 20, and the other end of the link 18 is pivoted between a pair of depending or downwardly projecting ears or flanges 21 carried by the bottom of the valve 7. The ears or flanges 21 are preferably located centrally of the valve, and a removable bolt or pivot element 22 is engaged through the ears 21 and respective end of the link 18, the ears 21 being preferably provided with a series of apertures 23 for the engagement of the 30 bolt 22 whereby the bolt may be removed and adjusted along the ears or flanges 21, to adjust the relation of the valve 7 and its actuating means or mechanism.

By swinging the lever arm 15, the valve 40 7 may be conveniently controlled, the parts being so arranged that when the arm 15 is swung to the position illustrated in Fig. 1, the arm 17 of the lever will swing adjacent the wall 6 of the hopper so that the link 45 18 will push the valve 7 to closed position. It is to be noted that when the valve 7 is swung to closed position, the arm 17 and link 18 will tend to straighten out, so that the valve 7 will move relatively slow when 50 it is at its closed position, and will move relatively fast when at its open position, as seen in Fig. 2. In other words, the movement of the valve is accelerated in order that it may be quickly moved to and from a 55 completely open position, and in order that the valve may be accurately or nicely set when partially closed, since the valve will move relatively slow with respect to the movement of the lever arm 15. In this 60 manner, the operator or attendant may quickly cut off the flow of the material from

the hopper, at the opportune moment, and may conveniently swing the valve 7 at a desired distance from the wall 5 of the hopper, to allow a certain restricted flow of the 65 material. It is also to be observed that when the valve 7 is opened, it is swung upwardly, so that whenever the handle 16 is released, the valve will gravitate to a closed position of itself, to automatically cut off 70 the flow of material. Furthermore, the valve is so positioned that the material thereon will readily run off of the same to prevent the material lodging upon the valve when it is opened. By adjusting the bolt 75 or pivot element 22, the valve 7 may be adjusted relative to the actuating mechanism, so that when the lever 15—17 is swung to close the valve 7, a predetermined slot or gap may be provided between the valve 7 80 and hopper wall 5. The valve or shutter 7 may be operated easily even when subjected to considerable pressure due to the weight of the material within the hopper.

What is claimed is:

1. A hopper having a lower outlet, a bail-shaped hanger straddling the hopper, one wall of the hopper having means receiving the yoke portion of the hanger for fulcruming the same to the hopper, the side edges 90 of the hopper outlet being curved about the fulcrum of the hanger as a center, a valve engaged upon the end portions of the hanger and movable along the said edges of the outlet, and adjustable elements engaged 95 upon the ends of the hanger and bearing against the valve to hold the same against the said edges of the outlet.

2. A hopper having opposite relatively long and short walls and an inclined outlet 100 between the lower ends of the said walls, a U-shaped hanger straddling the hopper, the relatively long wall of the hopper having means receiving the yoke portion of the hanger for fulcruming the same thereto, the 105 side edges of the outlet being curved about the yoke portion of the hanger as a center, a valve engaged upon the end portions of the hanger and movable along the said edges of the outlet, adjustable elements engaged 110 upon the ends of the hanger to hold the valve against said edges, a lever fulcrumed to the hopper adjacent the relatively short wall thereof, and a link connecting the lever 115 and valve.

In testimony that I claim the foregoing as my own, I have hereto affixed my signature in the presence of two witnesses.

EDWARD P. KENDALL.
